SHUFFLE BOARD GAME TABLE

Marley A. Smith, Porter County, Ind.
(15 Old Porter Road, Portage, Ind.)

Filed Sept. 8, 1964, Ser. No. 81,636

Term of patent 14 years

(Cl. D34—5)

I claim:

The ornamental design for a shuffle board game table, as shown.
